DISPLAY BASE FOR TOOTHBRUSH CONTAINERS

Baard Spydevold, Oslo, Norway, assignor to A/S W.
Jordan Borste & Penselvfabrik, Oslo, Norway.

Filed Mar. 3, 1972, Ser. No. 231,794

Claims priority, application Norway Sept. 6, 1971.

Term of patent 14 years

Int. Cl. D6—06

U.S. Cl. D6—194

FIG. 1 is a perspective view of a display base for toothbrush containers, showing my new design,

FIG. 2 is a front elevation view,

FIG. 3 is a top plan view,

FIG. 4 is an end elevational view,

FIG. 5 is an elevational sectional view taken along line V—V of FIG. 2.

I claim:

The ornamental design for a display base for toothbrush containers, as shown.
